WIRE REDUCING MACHINE

Lee Berkebil, Detroit, Mich., assignor to B. W. Manufacturing Company, Detroit, Mich., a corporation of Michigan

Application July 18, 1938, Serial No. 219,892

11 Claims. (Cl. 205—3)

This invention relates generally to wire reducing machines and refers more particularly to machines or attachments for machines for reducing the diameter of wire stock and the like:

5 One of the essential objects of the invention is to provide a self-contained unit of this type for drawing or extruding the wire stock.

Another object is to provide a unit wherein a 10 rotatable die is employed for reducing the diameter of the wire.

Another object is to provide a unit wherein a suitable mechanism for feeding the wire to the die is driven from the die operating means.

Another object is to provide means for rendering the feed mechanism inoperative so that the die alone may operate, for example, when suitable means is employed instead of or in addition to the feeding mechanism mentioned for pulling, instead of pushing, the wire through the die. In 15 this connection the construction and arrangement is such that the feeding mechanism mentioned may be used with the pulling means to move the wire through the die.

In the past dies employed in wire reducing machines have been either stationary or provided with longitudinal sliding or reciprocating movement. In practice it has been impractical to extrude a hot rolled stock of relatively small diameter, for example, .25 of an inch or less. 20 Usually the mill supplies all sizes of hot rolled stock within the same limitations (plus or minus so many thousandths). This makes the percentage of reduction on smaller sizes greater than the percentage of reduction on larger stock, 25 consequently the percentage of reduction on small stock may be so great that it is impossible to push the stock through the die without it upsetting or buckling or jamming in the die as well as in the straightening bushings.

30 When the die is not rotated all the energy is applied to pushing the stock through the die. When the die is rotated, the energy is divided between the force necessary to rotate the die on the stock and the force necessary to push the stock through the die, the speed of the die having a direct bearing on the amount of force exercised in pushing the stock through the die. The same holds true in drawing wire by pulling it through a rotating die as well as extruding wire by pushing it through a rotating die.

In the present instance small stock can be fed or pushed without buckling through the rotating die, less force being required to feed or push the stock through the die as the latter has a comparatively high R. P. M. Since less force is re-

quired, a pair of rolls may suffice to feed the stock through the die. Moreover, the common drive for the die and feed mechanism is such that the assembly may be built as a unit and may be used alone or as an attachment for a 5 machine having suitable stock feeding means as aforesaid, for example, for a machine having stock pulling means as shown in my pending application filed June 27, 1938, bearing Serial No. 216,134.

10 In the accompanying drawings:

Figure 1 is a side elevation of a machine embodying my invention;

Figure 2 is a top plan view thereof;

Figure 3 is an end elevation;

15 Figure 4 is an elevation of the opposite end of the machine;

Figure 5 is a sectional view taken substantially on the line 5—5 of Figure 2;

Figure 6 is a sectional view taken substantially on the line 6—6 of Figure 3.

Referring to the drawings, A is the rotating die, and B is the feed mechanism of an assembly embodying my invention. As shown, the die A is held by a set screw 1 in a holder 2 non-rotatably mounted in the inner end of a sleeve type shaft 3 journaled in bearings 4 and 5 respectively in a suitable powder box 6. Preferably the holder 2 is driven from the shaft 3 by pins 7 projecting endwise from the adjacent end of 25 the shaft 3. In the present instance these pins 7 are riveted to the shaft 3 and have heads 8 engaging slots 9 in the periphery of the die holder 2. The bearing 4 is a thrust bearing for the shaft 3 while the bearing 5 is preferably a roller bearing. A felt washer 10 is provided at the outer end of the roller bearing to prevent the escape of oil used for lubricating purposes while a retaining plate 11 is provided at the adjacent 30 end of the powder box to hold the roller bearing 5 and felt washer 10 in place.

12 and 13 respectively are bushings for the wire stock and are located in axial alignment with the die A and holder 2. Preferably the bushing 12 is secured to the rear wall 14 of the 45 powder box and serves to guide the wire stock from a suitable source such as a chuck (not shown) which may be similar to the feeder P in my application Serial No. 216,134 filed June 27, 1938, to the die A, while the bushing 13 is carried by the shaft 3 at the forward end thereof and serves to guide the wire stock to a predetermined point, for example, into a suitable 50 chuck (not shown) which may be similar to the feeder N in my pending application Serial No. 55

216,134 to advance the stock to a header. However, it should be understood that my wire reducing machine has substantially universal use in that it is adaptable for use with machines other than cold heading machines. For example, it may be used alone as a wire reducing machine, or as an attachment for wire forming or wire drawing machines, four-slide machines, etc.

10 15 is a spacer located within the sleeve type shaft 3 between the holder 2 and bushing 13, and 16, 17 and 18 respectively are aligned bores within said parts for the wire stock.

The feed mechanism B preferably comprises 15 a pair of cooperating rolls 19 and 20 which engage the stock 21 at diametrically opposite sides thereof and push it through the rotating die A. Preferably the lower roll 19 is fixed to a shaft 22 journaled in a frame 23 rigid with the powder box, while the roll 20 is fixed to a shaft 24 journaled in a spring pressed follower 25 that in turn is mounted to slide vertically in said frame. As shown, the follower 25 has a recess 26 containing a suitable spring 27 and a header 28 therefor, and an adjusting screw 29 threadedly engaging the frame 23 bears against said header 28 and causes the spring 27 to urge the roll 20 downwardly toward the roll 19 so that the proper engagement with the stock 21 will be obtained.

30 Fixed upon the shaft 22 of the lower roll 19 is a worm gear 30 that meshes constantly with a worm 31 fixed upon a shaft 32 journaled in spaced bosses 33 and 34 respectively of the powder box and in the frame 23.

35 Suspended from a base plate 35 for the powder box is an electric motor 36 having a shaft 37 connected by suitable reduction gearing 38, carried by the motor casing, to a secondary shaft 39. Sprocket wheels 40 and 41 respectively are 40 fixed to the shafts 39 and 32 respectively and are connected by a suitable chain 42. Thus, the drive from the motor 36 to the lower feed roll 19 is through the reduction gearing 38 and secondary shaft 39, sprocket 40, chain 42, sprocket 41, shaft 32, worm 31, worm gear 30 and shaft 22. In this connection it should be appreciated that the upper feed roll 20 may be operatively connected to the lower feed roll by suitable gearing (not shown) so that the upper feed roll 20 50 as well as the lower feed roll 19 would be power driven to push the stock through the die.

In the present instance the die A is rotated at relatively high R. P. M., and this is accomplished by providing a gear 43 on the sleeve type 55 shaft at its outer end and a gear 44 fixed on the shaft 32 and meshing with said gear 43. Thus, the die A and feed roll 19 will operate simultaneously when the motor 36 is in operation.

When the motor 36 is operating and the adjusting screw 29 is tightened so that the upper feed roll 20 is pressed by the spring 27 into operative relation with the stock 21, the upper feed roll will rotate with the lower power driven feed roll 19 to cause the stock to be pushed through the rotating die A. However, when the adjusting screw 29 is loosened so that the upper feed roll 20 is inoperative, the stock 21 will not be advanced or pushed by the lower feed roll 19 through the rotating die. In this case suitable 65 means such as a chuck (not shown) similar to N in my application Serial No. 216,134 may be employed in advance of the bushing 13 for pulling the stock through the die A which will be rotated by the motor. Thus, the die A may operate 70 simultaneously with or may operate without the

feed rolls, as desired. Moreover, it will be appreciated that the pulling means such as the chuck mentioned that I contemplate using in advance of the bushing 13 will not interfere with the operation of the feed rolls 19 and 20, consequently such chuck may, if desired, be used in addition to or as a substitute for the feed rolls to move the stock through the rotating die A. 5

From the foregoing it will be apparent that the rotating die A, feed mechanism B, and drive 10 means therefor cooperate with the powder box 6, frame 23 and base plate 35 to provide a self-contained unit that may be used alone as a wire reducing machine or that may be used with other machines or parts thereof, such, for example, 15 as the machine set forth in my application Serial No. 216,134. Moreover, my wire drawing machine is especially adaptable for use with chucks similar to P and N set forth in my application Serial No. 216,134 which may, of course, be set up without the cold heading mechanism. 20

What I claim as my invention is:

1. In a wire drawing machine, a powder box, a hollow shaft journaled in a wall of said box, a die holder within said box at the inner end 25 of said shaft, the periphery of said holder having longitudinally extending grooves, a die secured in said holder, and a driving connection between said shaft and holder including pins projecting endwise from said shaft, and engaging the longitudinally extending grooves in the periphery of said holder. 30

2. In a wire drawing machine, a hollow shaft, a die holder at the inner end of said shaft, the periphery of said holder having longitudinally extending grooves, a die secured in said holder, and a driving connection between said shaft and holder including pins projecting endwise from said shaft, and engaging the longitudinally extending grooves in the periphery of said holder. 40

3. In a wire drawing machine, a powder box, a hollow shaft journaled in a wall of said box, a die holder secured in the inner end of said shaft, a die secured to said holder, a shaft journaled in bearings upon the outside of said box, a 45 driving connection between said shafts, a worm on the second mentioned shaft, a pair of rolls for feeding stock through said hollow shaft, die holder and die, shafts for said rolls, a worm gear on one of the last two mentioned shafts meshing with the worm aforesaid, and power means for driving the second mentioned shaft. 50

4. In a wire drawing machine, a powder box, a hollow shaft journaled in a wall of said box, a die holder secured in the inner end of said shaft, a die secured to said holder, a pair of rolls for feeding stock through said shaft, holder and die, shafts for said rolls, a shaft journaled in bearings upon the outside of said box, means for driving the last mentioned shaft, a worm on 60 the last mentioned shaft, a worm gear on one of the two roll shafts meshing with said worm, a gear on the last mentioned shaft, and a gear on the hollow shaft meshing with the last mentioned gear. 65

5. In a wire drawing machine, a shaft, a die holder secured to an end of said shaft, a die secured to said holder, a pair of rolls for feeding stock through said die, shafts for said rolls, a 70 shaft substantially parallel to the first mentioned shaft, means for driving the last mentioned shaft, a worm on the last mentioned shaft, a worm gear on one of the two roll shafts meshing with said worm, a gear on the last mentioned shaft, and a 75 gear on the last mentioned shaft, and a 76

gear on the first mentioned shaft meshing with the last mentioned gear.

5 6. A wire reducing machine having a powder box, a rotatable shaft journaled in one wall of said box, a die holder carried by said shaft at its inner end within said box, said shaft and holder having aligned bores for the wire, and a guide bushing for the wire extending through the opposite wall of the box in alignment with the 10 aligned bores aforesaid.

10 7. A wire reducing machine having a powder box, a rotatable shaft journaled in one wall of said box, a die holder carried by said shaft at its inner end within said box, said shaft and holder having aligned bores for the wire, and guide bushings for the wire located respectively in rear and in advance of and in alignment with the aligned bores aforesaid, one of said bushings extending through the opposite wall of the box, 15 20 and the other of said bushings being located at the outer end of the shaft.

25 8. A wire reducing machine having a rotatable shaft, a die holder carried by said shaft, a second rotatable shaft, a driving connection between the second and first mentioned shafts including meshing gears carried respectively by said shafts, a pair of cooperating rolls for feeding wire through the holder, shafts for said rolls, one for each roll, and a driving connection between the 30 second shaft and one of said feed rolls including a worm gear on said feed roll shaft, and a worm on the second shaft meshing with said worm gear.

35 9. A wire reducing machine having a frame, a powder box adjacent said frame, a rotatable shaft journaled in a wall of the powder box, a die holder carried by said shaft within said powder box, a shaft journaled on the outside of said powder

box, a driving connection between the second and first mentioned shafts including meshing gears carried respectively by said shafts outside said box, a pair of cooperating rolls for feeding wire through the holder, shafts for said rolls, one for each shaft, one of said feed roll shafts being journaled in said frame, a spring pressed follower 5 slidably mounted on said frame, the other of said feed roll shafts being journaled in said follower, and a driving connection between the second 10 mentioned shaft and one of said feed roll shafts including a worm gear on said feed roll shaft, and a worm on the second mentioned shaft meshing with said worm gear.

15 10. A wire reducing machine having a powder box, a sleeve type shaft journaled in one upright wall of said box, a die holder carried by said shaft at its inner end within said box, substantially aligned guide bushings for the wire carried by said shaft and box, one of said bushings 20 being in said sleeve type shaft, and the other of said bushings extending through the opposite upright wall of the box, and a die carried by said holder between and substantially in alignment with said bushings.

25 11. A wire reducing machine having a powder box, a rotatable sleeve type shaft journaled in one upright wall of said box, a die holder carried by said shaft at its inner end within said box, a die carried by said holder, and guide bushings for 30 the wire located respectively in rear and in advance of and in alignment with said die, one of said bushings being secured to the opposite upright wall of the box, and the other of said bushings being at the outer end of said shaft.

35

LEE BERKEBIL.
